126,826

DESIGN FOR A COMBINED DISPLAY CONTAINER AND CHEWING GUM, CANDY, OR THE LIKE

Jack Lane, New York, N. Y.

Application October 15, 1940, Serial No. 95,849

Term of patent 14 years

To all whom it may concern:

Be it known that I, Jack Lane, a citizen of the United States, residing at New York city, in the county of the Bronx and State of New York, have invented a new, original, and ornamental Design for a Combined Display Container and Chewing Gum, Candy, or the like, of which the following is a specification, reference being had to the accompanying drawing, forming part thereof.

The figure is a perspective view of a combined display container and chewing gum, candy, or the like, showing my new design.

The characteristic features of the design reside in the ornamentation on a panel of the container as indicated by the lines on the drawing, surrounding the elongated opening in said panel, said opening exposing to view chewing gum tablets, or the like, which appear in said opening, as shown.

I claim:

The ornamental design for a combined display container and chewing gum, candy, or the like, substantially as shown and described.

JACK LANE.
